US00D853440S

(12) United States Design Patent (10) Patent No.: US D853,440 S
(45) Date of Patent: * Jul. 9, 2019

(54) DISPLAY SCREEN OR PORTION THEREOF WITH ICON

(71) Applicant: Samsung Electronics Co., Ltd., Suwon-si (KR)

(72) Inventors: Jinhee Kwon, Seoul (KR); Jiwon Yoo, Yongin-si (KR)

(73) Assignee: SAMSUNG ELECTRONICS CO., LTD., Suwon-si (KR)

() Term: 15 Years

(21) Appl. No.: 29/573,202

(22) Filed: Aug. 3, 2016

(30) Foreign Application Priority Data

Jun. 3, 2016 (KR) 30-2016-0027216

(57) CLAIM

The ornamental design for a display screen or portion thereof with icon, as shown and described.

DESCRIPTION

The FIGURE is a front view of a display screen or portion thereof with icon showing our new design.

The outer perimeter illustrated by a pair of broken lines in the FIGURE depicts a display screen or portion thereof and forms no part of the claimed design.

The areas of tonal contrast in the FIGURE depict a contrast of appearance.

1 Claim, 1 Drawing Sheet
